UNITED STATES PATENT OFFICE.

HANS BUCHNER, OF MUNICH, GERMANY.

BOOT AND SHOE TREE.

1,130,707.

Specification of Letters Patent. Patented Mar. 9, 1915.

Application filed August 27, 1912. Serial No. 717,326.

To all whom it may concern:

Be it known that I, HANS BUCHNER, a subject of the German Emperor, and residing at Munich, Bavaria, German Empire, have invented certain new and useful Improvements in Boot and Shoe Trees, of which the following is a specification.

This invention pertains to hollow trees designed for warming and drying boots and shoes, and it relates particularly to improvements for enabling thorough ventilation and rapid and complete evaporation and escape of the moisture in the shoe, while affording proper support for the latter during the operation and thus preserving its correct shape.

A preferred embodiment of my invention is illustrated in the accompanying drawing.

Figures 1 and 2 are perspective views of the body and heel portions of the tree respectively. Fig. 3 is a perspective view of the assembled tree, exhibiting in particular the sole thereof. Fig. 4 is a horizontal section showing the tree applied to a shoe. Fig. 5 is a similar view to Fig. 3, but drawn to a smaller scale and showing the two members of the tree separated, the channeling moreover being omitted for the sake of clearness in the drawing.

The tree comprises a suitable number of matching sections, there being in the particular embodiment illustrated only two such, viz. a body-portion *a* and a heel-portion *b*, fitted thereto with tongue and groove joint *e*, *e*. Both sections *a*, *b*, are hollow, each constituting a receptacle to contain hot-water or other heating-liquid, or some medium which generates heat by chemical reaction. The two parts *a*, *b*, may be advantageously made of aluminium, or some other light but strong material, and each may be furnished with an openable cover of any suitable description, or may be closed over at the top and be there provided with a screw-stopper or the like in well-known manner. The entire surface of the two sections *a*, *b*, (with the exception of the joining faces where the tongue and groove *e*, *e*, are located) is fluted, channeled or grooved, in such manner as to present an assemblage of closely contiguous passages *c* for the flow of air and vapor. The ribs or ridges *d* sepa-

rating the individual grooves *c* are shown as being interrupted at *f* on the sole of the tree, whereby the various ducts *c* are brought into communication. When the tree is applied to a shoe, the vapor flowing up the passages *c* forms between the tree-walls and the material of the shoe *g* (Fig. 4) an insulating layer, which is only interrupted by the narrow ribs *d* which separate adjacent grooves. Thus with my improved tree the vapor which rises during drying of the shoe has a free passage for escape from all parts of the article, and the warm air in the ducts constitutes, as it were, a jacket which serves to equalize the heat radiated by the different parts of the tree and impart it uniformly to the walls of the shoe. A particular advantage of the improved grooved construction is thus seen to be that although perfect support is afforded to the material of the shoe at all places, for the purpose of preventing creasing and maintaining an even surface and regular shape, vapor can pass off at every part and warm air can act directly and with full effect on the material, which is uncovered by any intervening surface, the ribs *d* being so narrow as to form no material obstruction. The new tree is, therefore, especially suited for fine or delicate leathers, such as kid, patent leather, and the like.

It will be observed that the improved tree is especially adapted for the use of travelers, tourists, etc., since the sections can be utilized as cooking or drinking vessels, as hot-water bottles, or the like.

Having thus described my invention, I claim as new—

1. A boot and shoe tree whose body constitutes a liquid container and whose surface is covered with grooves separated by narrow ribs, which extend upwardly from the sole, where they run substantially parallel with each other in transverse direction.

2. A boot and shoe tree whose body constitutes a liquid container and whose surface is covered with grooves separated by narrow ribs, which extend upwardly from the sole, where they are directed substantially at right angles to the longitudinal sole-axis, along which they are interrupted.

3. A boot or shoe tree whose body con-

stitutes a liquid container and whose surface is covered with grooves separated by narrow ribs, extending upwardly from the sole, which latter presents a passage located 5 substantially in its longitudinal axis and communicating throughout its length with the said grooves through thin-walled channels directed substantially at right angles to

the sole-axis and each leading to one of the said grooves.

In testimony whereof I affix my signature in presence of two witnesses.

HANS BUCHNER.
